UNITED STATES PATENT OFFICE.

RICHARD J. GREENWAY, OF WESTERLY, RHODE ISLAND, ASSIGNOR TO C. B. COTTRELL & SONS COMPANY, OF STONINGTON, CONNECTICUT, A CORPORATION OF DELAWARE.

ANTIOFFSET MECHANISM FOR PRINTING PRESSES.

Application filed March 3, 1925. Serial No. 12,843.

The object of my invention is to provide certain improvements in the construction, form and arrangement of the several elements of the anti-offset mechanism whereby 5 the anti-offset powder may be efficiently and thoroughly applied without waste, to the freshly printed side of the sheet or web; said elements including a traveling endless belt arranged for contact (preferably extended contact) with the sheet or web while 10 on its carrier, an anti-offset powder supply fountain and a fountain roll arranged to apply the powder directly to the belt for transfer thereby onto the freshly printed 15 side of the sheet or web.

A practical embodiment of my invention is represented in the accompanying drawings, in which

Fig. 1 represents in side elevation so much 20 of a printing press as includes my improved anti-offset mechanism.

Fig. 2 represents a vertical section through the same.

The rotary carrier is herein shown as a 25 sheet carrying cylinder 1 provided with sheet grippers 2, the shaft 3 of which cylinder is suitably mounted in the frame 4.

The endless belt 5 passes around the drive roll 6, the idler rolls 7 and 8 and the belt 30 tightener roll 9. These rolls are all suitably mounted in the frame 4 and the rolls 7 and 8 are so arranged so as to cause the endless belt 5 to have an extended contact with the freshly printed side of the sheet on 35 the carrier.

The anti-offset powder supply fountain is denoted by 10 and its roll 11 is arranged in 40 position to apply the anti-offset powder directly to the endless belt 5 for transfer thereby onto the freshly printed side of the sheet.

An adjustable doctor knife 12 is mounted in the fountain 10 in position to regulate the amount of anti-offset powder applied by 45 the fountain roll to the endless belt.

The carrier, the endless belt and the fountain roll are driven at the same surface speed from the carrier gear 13 through the gear 14, shaft 15, bevel gears 16 and 17, 50 shaft 18, bevel gears 19 and 20 and gears 21 and 22.

It will be seen that by this arrangement I am enabled to apply the anti-offset powder to the freshly printed side of the sheet

or web in regulable quantities so that all 55 waste of the powder may be eliminated and also so that too much powder need not be applied to the freshly printed side of the sheet or web.

It is evident that various changes may be 60 resorted to in the construction, form and arrangement of the several parts without departing from the spirit and scope of my invention; hence, I do not intend to limit myself to the particular embodiment herein 65 shown and described, but

What I claim is:

1. A rotary carrier for a freshly printed sheet or web, a traveling endless belt arranged for contact with the sheet or web 70 while on the carrier, an anti-offset powder supply fountain, and a fountain roll to apply the powder directly to the belt for transfer thereby onto the freshly printed 75 outer side of the sheet or web.

2. A rotary carrier for a freshly printed sheet or web, a traveling endless belt arranged for extended contact with the sheet or web while on the carrier, an anti-offset powder supply fountain, and a fountain roll 80 to apply the powder directly to the belt for transfer thereby onto the freshly printed outer side of the sheet or web.

3. A rotary carrier for a freshly printed sheet or web, a traveling endless belt, arranged for contact with the sheet or web while on the carrier, an anti-offset powder supply fountain, and a fountain roll to apply the powder directly to the belt for transfer thereby onto the freshly printed 85 outer side of the sheet or web, the carrier, belt and roll being driven at the same surface speed.

4. A rotary carrier for a freshly printed sheet or web, a traveling endless belt arranged for extended contact with the sheet or web while on the carrier, an anti-offset powder supply fountain, and a fountain roll to apply the powder directly to the belt for transfer thereby onto the freshly printed 90 outer side of the sheet or web, the carrier, belt and roll being driven at the same surface speed.

In testimony, that I claim the foregoing as my invention, I have signed my name this 1 27th day of February, A. D. 1925.

RICHARD J. GREENWAY.
